UNITED STATES PATENT OFFICE.

WILLIAM H. COTTON, OF SALEM, NEW YORK.

FOUNTAIN.

1,130,800.

Specification of Letters Patent. Patented Mar. 9, 1915.

Application filed September 25, 1913. Serial No. 791,813.

To all whom it may concern:

Be it known that I, WILLIAM H. COTTON, a citizen of the United States of America, residing at Salem, in the county of Washington and State of New York, have invented certain new and useful Improvements in Fountains, of which the following is a specification, reference being had thereto to the accompanying drawing.

10 This invention relates to an improved fountain which is intended to be used for fowls such as chickens, and the principal object of the invention is to provide a fountain which is easy to clean and which is so 15 constructed that the water can be easily dumped out when it is desired to provide a fresh supply of water.

Another object of the invention is to so construct the fountain that the cover which 20 closes the cleaning opening will be protected and prevented from being injured in case the fountain is struck by any object.

With these and other objects in view this 25 invention consists of certain novel combinations, constructions, and arrangements of parts as will be hereinafter fully described and claimed.

This invention is illustrated in the accompanying drawings, wherein:

30 Figure 1 is a perspective view of the fountain in a position ready for use. Fig. 2 is a front elevation of the fountain. Fig. 3 is a longitudinal sectional view through the forward portion of the fountain. Fig. 4 is a 35 fragmentary perspective view of that portion of the front wall with which the closure cap is connected.

This fountain is provided with an outer receptacle 10 and an inner receptacle 11 40 which is tapered as shown in Fig. 3, and has its lower edge terminating adjacent the front wall 12 which closes the lower half of the forward end of the outer receptacle. The inner receptacle is provided with a front 45 wall 13 extending from the upper edge to a point approximately on a level with the upper edge of the front wall 12, thus providing a space between the two walls 12 and 13 through which the chickens may obtain 50 access to the water in the inner receptacle. A wire netting 14 is placed across this opening and is provided so that small chickens will be prevented from falling into the

water and becoming drowned when they jump up upon the upper edge of the front 55 wall 12 in order to obtain a drink of water.

The front wall 13 of the inner receptacle is sloped inwardly, as shown in Fig. 3, to such an extent that the cap 15 which is secured upon the threaded neck 16 will be 60 positioned within the space between the wall 13 and the edge of the outer receptacle. This protects the cap and prevents any danger of its being hit and either broken or mashed out of shape by any object striking 65 the fountain. This cap is provided so that when it is desired to clean the fountain, the cap may be removed and the water in the fountain permitted to freely flow out of the inner receptacle through the neck 16 and 70 through the opening which is covered by the wire 14. If it were not for this opening, the water could not very readily flow out through the opening covered by the wire 14 and, therefore, it would take some time to 75 empty the fountain. It should also be noted that when the cap is removed, the person cleaning the fountain can put his hand into the inner receptacle through the neck and thus more readily clean the interior of the 80 fountain.

A handle 17 is carried by the ears 18 and is intended to be engaged by the clips 19 so that the handle will provide means for keeping the fountain in the position shown 85 in Fig. 1.

What is claimed is:-

In a drinking fountain of the class described the combination with an outer receptacle, an inner receptacle positioned within 90 said outer receptacle, said inner receptacle provided with converging sides, thereby forming a dead-air space between said inner and outer receptacles, said inner receptacle provided upon its lower portion with a vertical front wall, a slanting front wall formed integral upon said inner receptacle so that the lower end of said slanting front wall will be spaced at a distance from the upper portion of said vertical front wall, 95 the forward portion of said outer receptacle extending for a distance beyond the forward face of said slanting wall of said slanting receptacle, said inner wall provided with an enlarged hand opening, a threaded neck 100 formed about said enlarged opening, a cap 105

threaded into engagement with said neck for forming a closure for said opening, said cap adapted to be removed to allow a person to pass a hand through said opening for cleaning the interior of said inner receptacle, said body and neck being positioned within said outer receptacle so as to prevent a foreign object from swinging across the front of said drinking fountain and knock-

ing the cap from engagement with said neck.

In testimony whereof I hereunto affix my signature in presence of two witnesses.

WILLIAM H. COTTON.
